CORDED SEAM

Creston A. Smith, Philadelphia, Pa.

Application August 20, 1947, Serial No. 769,657

8 Claims. (Cl. 155—184)

1

This invention relates to improved self-locking seaming strips or cords for use on upholstered furniture or the like and to a method and apparatus for forming corded seams, the present invention being an improvement over that disclosed in my prior pending application, Serial No. 718,191, filed December 24, 1946, now Patent No. 2,496,820, issued February 7, 1950.

An object of my present invention is to provide, as a separate article of manufacture, a flexible strip-like means which will serve as a seaming cord for binding therein the marginal edges of fabrics to be joined together, the seaming strip being so constructed as to be self-locking in compacted condition with the said marginal edges of the fabrics to be joined together securely gripped within the closed seam by the said locking means.

Another object of the present invention is to provide a simple manually operated device by means of which the said self-locking flexible seaming cord strip may be easily and readily locked in position over the marginal edges of fabrics to be joined together to form tightly filled corded seams.

A still further object of the present invention is to provide in a self-locking flexible seaming strip which is adapted to be folded longitudinally thereof about the marginal edges of fabrics to be joined together, means centrally disposed along one face of said seaming strip which will serve to guide and properly position the said marginal edges within said corded seam and which means will also serve as a filling for the cord conjointly with the said marginal edges of the fabrics to be joined together to tightly fill said corded seam so that the same will present a desirable appearance.

Still another object of the present invention is to provide in a self-locking flexible seaming strip, self-locking means which comprise barb tipped fingers secured within and projecting transversely from each of the longitudinal beaded edges of the said strip, the said fingers being provided with heads which serve to securely fasten the same within the said beaded edges.

Another object of the invention is the provision of an improved method of forming tightly filled corded seams which includes the step of juxtaposing the marginal edges of fabrics to be joined together to form seam allowances, the step of placing a flexible self-locking seaming strip in enveloping relation upon said seam allowances with each of said marginal edges within a guide groove formed in said strip, and the

2

step of forming the corded seam by causing the self-locking means of the strip to bind the interlocked marginal edges of the fabrics and the strip together in a single and continuous operation.

These and other objects of the invention will be apparent from the following description thereof taken in connection with the accompanying drawings in which—

Figure 1 is a perspective view of the self-locking flexible seaming strip of my invention shown in position over the marginal edges of fabrics which are joined together thereby within a tightly filled corded seam and the lacing means forming said seam;

Figure 2 is a perspective view of the outer face of my improved self-locking flexible seaming strip;

Figure 3 is a view similar to Figure 2 showing the inner face of the seaming strip;

Figure 4 is a cross-sectional view showing the condition of the corded seam at the commencement of the binding operation;

Figure 5 is a cross-sectional view of the finished corded seam;

Figure 6 is a perspective view of the binding device;

Figure 7 is a cross sectional view of the binding device taken on the line 7—7 of Figure 6;

Figure 8 is a cross-sectional view of the binding device taken on the line 8—8 of Figure 6; and

Figure 9 is a cross-sectional view of the binding device taken on line 9—9 of Figure 8.

Referring now to Figures 1, 4 and 5 it will be seen that fabrics 10 and 11 which may form the cover of upholstered furniture or the like and are to be joined together have their marginal edges turned as at 12 and 13 and arranged in juxtaposition to provide material for a closing seam.

The seam allowance edges 12 and 13 are embraced within the seaming cord or strip 14 which preferably consists of a flexible strip-like piece of textile or other material whose lengthwise extending marginal edges are rolled over and suitably secured to cores 15 of such material as compressed felt, rubber or compacted cotton to form the side beads 16 and 17. Also secured to the strip 14 on the under surface thereof is a lengthwise extending core 18, triangular in cross section, which is spaced midway between the side beads 16 and 17, this intermediate core 18 being of a material similar to that of the cores 15—15. One flat base of the triangular core 18 is secured to the strip 14 while the remain-

ing relatively inclined faces are freely disposed to respectively fit against corresponding flat faces of the beads 16 and 17 when the seaming strip 14 is in compacted condition with the marginal ends 12 and 13 of the fabrics to be joined together disposed therebetween, all as clearly appears in Figures 1 and 5.

A plurality of laterally projecting fastening or locking elements 19, each consisting of a shank having a freely extending barb 20 at one end and an anchoring tail 21 at the other end, are suitably embedded and secured within the cores 15-15 of the beads 16 and 17. The barbed fastening elements 19 project transversely of the bead 16, as shown in Figure 3 in staggered relation to the corresponding elements 19 in the opposite bead 17. The relative arrangement of these barbed elements 19-19 is such that as the cord 14 is compacted, as shown in Figures 1 and 5, with the marginal edges 12 and 13 of the fabrics lying between the opposite faces of the core 18 and the beads 16 and 17, respectively, the barbed ends of the elements 19 on the beads 16 and 17 are caused to move toward each other to pierce the two fabrics 10 and 11 disposed therebetween and to enter and be retained within the oppositely disposed cores 15-15 of the beads 16 and 17. It will be noted that the anchoring extremities of the fastening elements 19 provide the means by which the said elements are securely held within the cores 15-15 against displacement therefrom during subsequent use of the finished corded seam.

It will also be noted that the inclusion of the central core 18 in the seaming strip 14 provides the means for positioning the marginal ends 12 and 13 of the fabrics 10 and 11 within the finished corded seam and also acts as a filling means, conjointly with the said marginal ends, to completely fill the finished seam so as to render it substantially solid and of compact and neat appearance. The parts are proportioned so that there is just enough material of the strip 14 at 21 extending between the central core 18 and the side beads 16 and 17 to cover the otherwise free side faces of the core 18 when the seaming strip is in its compacted condition as shown in Figure 5.

It is obvious that any suitable means may be employed for positioning the cord upon the seam allowance marginal ends and for passing the barbed fasteners therethrough and into the oppositely disposed beads to form the corded seam. While in some instances the invention may be practiced by performing these operations manually, a particularly efficient means for compacting the seaming strip into cord form is disclosed in the device shown in Figures 6, 7, 8 and 9.

The last-mentioned means comprises a binding device 22 having die surfaces incorporated therein. This device, which may be conveniently made of metal or of plastic composition, is preferably constructed as a unitary member operable manually by the user. As shown, the binding device 22 comprises a flared, generally tubular body member 23 terminating at its lower side in a pair of laterally spaced flattened portions 24-24, each of which latter is provided with an upstanding lip 25. The body 23 tapers in transverse dimension from the widened inlet end 26 to the narrow discharge end 27, said body being internally provided with a pair of relatively inclined tongues 28-28 extending downwardly from each side of the top of the body 23 for a portion of the length thereof toward the center.

The tapered body 23 and the flattened bottom

portions 24-24 provide in effect two tapered opposing channels between which the seaming cord 14 is accommodated during movement of the binding device lengthwise of the seaming strip 14 to be compacted as shown in Figure 1. During such passage of the device over the cord, the depending tongues 28-28 are in contact with the cord and fold the material of the same between the central bore 18 and the side beads 16 and 17. A channel is formed between each tongue 28 and each flat piece 24 and lip 25 within which each of the beads 16 and 17 may enter. Likewise a channel is formed between the depending tongues 28-28 and the body 23 within which the central core 18 may enter. Inasmuch as the device 22 tapers from the larger inlet end thereof, at 26, to the smaller discharge end, at 27, it will be obvious that the channels previously described converge relatively to each other so that the respective parts of the cord are progressively forced toward each other until at the constricted discharge end of the device the parts of the cord are compacted into seamed and locked relation with the barbed elements 19 piercing the marginal ends 12 and 13 and caught within the beads 16 and 17.

From the foregoing explanation, the manner of using the binding device will now be apparent. When it is desired to make a corded seam between two pieces of fabric 10 and 11, the marginal edges 12 and 13 of said fabrics are arranged into juxtaposition, and then placed inside one end of a length of seaming cord on each side respectively of the central core 18. The beads 16 and 17 are then brought into position to hold the marginal ends of the fabrics therebetween and to force the barbed elements 19 through the marginal ends 12 and 13 and into the opposite cores 15-15 of the beads 16 and 17. This operation is preferably commenced as a hand operation, following which the binding device 22 is placed with the started end of the seaming cord entering the inlet end 26 of said device, the respective parts of the seaming cord entering the channels previously described. The binding device 22 is now moved manually longitudinally along the marginal ends of the fabric to be joined together in the direction indicated by the arrow in Figure 1, and the converging channels of the binding device then force the parts of the seaming cord toward each other so that the barbed elements 19 are progressively forced toward each other through the said marginal ends 12 and 13 and into the oppositely disposed cores 15-15 of the beads 16 and 17, thus completing the seaming of the cord as the device 22 passes thereover. The depending tongues 28-28 enter between the central core 18 and the side beads 16 and 17 to force the fabric of the seaming strip 14 down alongside the marginal ends 12 and 13 to form a neat and tight seam. The parts are now in locked position and the corded seam is complete.

It will be understood, of course, that the invention herein described is susceptible of various changes and modifications which may be made from time to time without departing from the general principles or real spirit thereof, and it is accordingly intended to claim the same broadly, as well as specifically, as indicated by the appended claims.

What is claimed as new and useful is:

1. A seaming strip for making corded seams comprising a strip of flexible material having lengthwise extending spaced raised portions in

the center and along the marginal edges thereof, each of said marginal edge portions having self-containing means for engagement with the other marginal edge portion.

2. A seaming strip for making corded seams comprising a strip of flexible material having lengthwise extending spaced raised portions in the center and along the marginal edges thereof, each of said marginal edge portions carrying its own self-contained means for locking engagement with the other marginal edge portion.

3. A seaming strip for making corded seams comprising a strip of flexible material having a longitudinally extending raised portion along the center thereof, each of the marginal edges of said strip being formed with self-contained means for locking engagement with the other marginal edge.

4. A seaming strip for making corded seams comprising a strip of flexible material having beads formed along the marginal edges thereof, locking pins secured at intervals along and in said beads and projecting laterally therefrom, heads on said pins within said beads, and barbs on the projecting ends of said pins for locking engagement with the opposite bead.

5. A seaming strip for making corded seams comprising a strip of flexible material having beads formed along the marginal edges thereof, a band of triangular cross section extending lengthwise of said strip in the center thereof and spaced from said marginal beads, said marginal beads each carrying its own self-contained means for locking engagement with the other marginal bead.

6. A corded seam consisting of the marginal portions of fabrics to be joined together and a seaming strip embracing said marginal portions

in juxtaposed position, said strip carrying its own means extending through said marginal portions to lock said strip in fabric embracing relation to form said seam and a filler forming part of said strip extending between said marginal portions of the fabric.

7. A corded seam consisting of the marginal portions of fabrics to be joined together, a filler and a seaming strip embracing said marginal portions and said filler with the latter extending between the marginal portions, said strip carrying its own means for locking itself in said embracing relation to form said corded seam.

8. A corded seam consisting of the marginal portions of fabrics to be joined together and a seaming strip embracing said marginal portions, said strip having a longitudinally extending filler along its center and longitudinally extending beads formed along its marginal edges, said beads each carrying self-contained means for locking engagement with the other bead to hold said strip in said fabric embracing relation to form said seam, said means penetrating said marginal portions and said filler extending between said marginal portions.
